Des. No 7.

John Martino and James Norton
of Philadelphia Penn.
Assignors to Thos. H. Peterson,
Letter Patent No. 1607 dated June 17, 1862.

The schedule referred to in these Letters Patent and making part of the same.

Wes. 1607

2

To all whom it may concern.

Be it known that we John Martin and James Norton, of Philadelphia, County of Philadelphia, State of Pennsylvania, have invented or produced a new and original design for Cook Stove, and they do hereby declare the accompanying drawing with the following explanation of the same to form a full, clear and exact description of the said Design.

Fig. 1. of the drawing represents a side view of the stove.

Fig. 2. a front view.

Fig. 3. a plan view, and

Fig. 4. a view of sufficient of the rear plate of the stove, to illustrate the ornamentation of the same.

The side plates of the stove, one of which is represented in Fig. 1, has a large door A, and a smaller door B, both being edged with mouldings formed of plain and denticulated beads, the space enclosed by these mouldings, in both doors, having in relief the figure of a harp intertwined with foliated ornaments.

Above the large door is a panel D, edged with a plain moulding and containing harps connected together by foliated ornaments as in the ornament beneath the large door A.

Above the small door B, is a panel E, formed by plain mouldings and containing a harp with foliated ornament.

The upper front plate I, (Fig. 2,) of the stove, is edged at the opposite ends with plain vertical mouldings, and has two doors G, G', with mouldings and ornaments similar to those of the door B, of the side plate of the stove.

The lower front plate II, is edged at the opposite ends with plain vertical mouldings similar to those of the upper front plate and has a panel I, with mouldings similar to those of the doors of the side plate.

The top plate J, is of the form represented in Fig. 3, and edged with a plain moulding, and the ash pit plated with a moulding composed of plain and denticulated beads precisely similar to the moulding on the doors A and B; the cover plate I, of the ash pit having a

Des. 1607

panel edged with a simple denticulated moulding and containing the words "Golden Harp, Stuart & Peterson Philadelphia."

The rear plate is ornamented by panels formed by plain and denticulated mouldings, as clearly represented in Fig. 4.

We claim the ornamental figures and forms, represented in and by the accompanying drawing, and forming together an ornamental design for a cooking stove.

In testimony whereof we have signed our names to this specification in the presence of two subscribing witnesses.

Witnesses.

William J. Goffin.
Joseph G. Miller.
